[57] CLAIM

The ornamental design for a sound actuated night light, substantially as shown and described.

DESCRIPTION

FIG. 1 is a top, front left-hand side perspective view of a sound actuated night light showing our new design; FIG. 2 is a front elevational view thereof on a slightly enlarged scale;

FIG. 3 is a right-hand side elevational view thereof on a slightly enlarged scale;

FIG. 4 is a rear elevational view thereof on a slightly enlarged scale;

FIG. 5 is a bottom plan view thereof on a slightly enlarged scale.

FIG. 1

FIG. 4

FIG. 2

FIG. 3

FIG. 5
